UNITED STATES PATENT OFFICE

SIGMUND REST, OF CHICAGO, ILLINOIS

ADVERTISING DEVICE

Application filed April 4, 1932. Serial No. 602,976.

My invention relates to advertising, and includes among its objects and advantages the provision of an improved traveling sign.

In the accompanying drawings:

- 5 Figure 1 is a front elevation of my device;
- Figure 2 is an enlarged sectional view taken along the line 2—2 of Figure 3;
- 10 Figure 3 is an enlarged sectional view taken along the line 3—3 of Figure 2;
- Figure 4 is a transverse sectional view taken 15 along the line 4—4 of Figure 3;
- Figure 5 is a transverse sectional view taken along the line 5—5 of Figure 3;

Figure 6 is an enlarged detail view taken 20 along the line 6—6 of Figure 3 illustrating the use of an alternating-current motor; and

Figure 7 is a similar view illustrating the use of a direct-current motor.

In the embodiment of the invention selected 25 for illustration, I make use of a casing 10 comprising a front wall 12, a back wall 14, a top 16 and end walls 18 and 20. The bottom of the casing is open with the exception of two bars 22 which extend the full length of 30 the casing. A third bar 24 is associated with the bars 22 through the medium of two rectangular rings 26 formed of strap material similar to the bars 22 and 24. Each ring is positioned adjacent its respective end of 35 the casing 10 and is welded to the bars 22 and 24.

Each end of the bar 24 is bent to provide a portion 28 which is fastened to its respective end of the casing by a screw 30. L-shaped 40 members 32 are welded to the upper front corners of the rings 26 and fastened to the ends of the casing by a screw 34. The legs of these members running parallel to the front wall 12 are no longer than the width of the 45 rings 26. The bars 22 and 24 and the rings 26 provide a supporting framework for the apparatus mounted within the casing.

The front wall 12 is provided with an opening 36 which is closed by a glass plate 38 50 adjacent the inner surface of the wall. I have provided clips 40 and 42 for holding the glass in assembly with the wall. This glass may easily be removed from the casing by merely removing the clips 42 and pulling the glass 55 through the open bottom. Referring to Figure 1, I have shown the lower portion of the glass as having a frosted area 44 and a clear or transparent area 46. The transparent area 46 is aligned with a reach 48 of a moving ribbon 50. The reach 48 extends substantially

the full length of the casing and is positioned close to the glass plate 38.

The ribbon 50 comprises transparent wadded silk and is provided with reading matter indicated at 52 in Figure 1. This reading matter is painted on the ribbon and has opaque properties so as to be distinctly visible through the glass 38 when the interior of the casing is illuminated. I have found that various types of ribbon may be used with 60 equally good results, such as an opaque ribbon provided with perforations defining the reading matter, or an opaque ribbon having transparent areas defining the reading matter. The frosted area 44 may be utilized for 65 advertising purposes.

In Figure 2, I have shown the ribbon passing around a series of spools 54 to 62, inclusive. This arrangement divides the ribbon 50 into three reaches 64, 66, and 68 in addition to the reach 48. It will be noted that I have arranged the spools in such a manner that a relatively long ribbon may be used in a cabinet of relatively small dimensions. Illumination is provided by electric 70 light bulbs 70 fitting into sockets 72 electrically connected with conductors 74. These sockets are fastened to a strap 76 having its ends welded to the bars 22 at 78. In referring to Figure 4, it will be noted that 75 the bulbs 70 are positioned below the ribbon 50, and are arranged so that the diagonal reach 64 will not cast a shadow on the reach 48, thus providing effective illumination.

The spool 54 is power driven by means of 80 a direct-current motor 80, while the remaining spools are of the idle type. Spools 56, 58 and 60 are associated with supporting brackets 82, 84, and 86, respectively. These 85 brackets are welded to the rings 26. The spools are provided with pointed shaft portions 88 which turn in recesses in the brackets, while the opposite ends of the sleeves are provided with similar shaft portions associated with adjustable bearing elements 90. The spool 62 is associated with a bracket 92 90 pivotally mounted at 94 upon one of the rings 26 (see Figures 2 and 4). In referring to Figure 4, it will be noted that the bracket 92 95 comprises an arm portion 96 and a companion arm 98 welded thereto. The arm 98 is recessed for accommodating the shaft 88 carrying the spool and the adjustable bearing element 90 for the spool is associated with the 100 companion arm 98.

It will be noted that the bracket 92 is connected with a spring 100 which tends to swing the bracket in a direction placing the ribbon 50 under tension. This spring-pressed bracket provides compensation for slack in the ribbon and also places the ribbon under proper operating tension. In Figure 4, I have shown the companion arm 98 as being slightly cut away at 102 to provide accommodation for the short transverse stretch 104 of the ribbon 50.

The motor 80 comprises in part an outer shell 106 formed of insulating material. Metal plates 108 and 110 are clamped against the ends of the shell 106 by means of bolts 112 (see Figure 5) passing through bushings 114. The lower end of the motor rests upon a cross bar 109 and one of the rings 26. Bolts 111 passing through the cross bar 109 and the ring 26 clamp the motor firmly in position. A pair of plates 116 and 118 is mounted upon the plate 110. These plates are held in spaced-apart relation by means of sleeves 120 which have threaded relation with the bolts 112. Screws 122 have threaded relation with the bushings 120 for fastening the plate 118.

The space between the plates 116 and 118 house the speed reducing gearing 124 which connects the motor with the spool 54. Referring to Figure 6, I have shown a pinion 126 mounted upon the motor shaft 128 and housed within a tubular member 130. This pinion is arranged in mesh with a gear 132 mounted upon a shaft 134 journaled in the plates 116 and 118. I provide a slot 136 in the wall of the tubular member 130 to accommodate the gear 132. A small gear 138 is mounted upon the shaft 134 and is arranged in mesh with a large gear 140 mounted upon a shaft 142 directly connected with the spool 54. The lower end of this shaft is journaled in the plate 116 and the upper end of the shaft is pointed and associated with a bearing element 90 carried by a bracket 144 secured to one of the rings 126 by means of screws 146.

The gearing 124 provides a gear reduction suitable for a direct-current motor of given speed for driving the ribbon 50 at a predetermined speed. When an alternating-current motor is to be used, a different gear reduction will be necessary in order to run the ribbon at the same rate of speed. I have provided a construction which permits motors of either type to be employed without necessitating reconstruction of the device. In Figure 7, I have shown an alternating-current motor connected with the spool 54. At this time, I employ the pinion 126 and the gear 132 only, but I substitute the shaft 142 for the shaft 134 so that the spool will be directly connected with gear 132. To facilitate this change, I merely provide an extra shaft 142 having a gear fixed thereto of the same size as the gear 132. It

is necessary to shift the bracket 144 when making this change to align the axis of the spool 54 with the axis of the shaft 134 illustrated in Figure 6. A slightly shorter bracket 144 will be required, and the ring 26 is provided with two sets of screw openings for receiving the fastening screws 146. The spring-pressed bracket 92 will yield to permit shifting of the spool 54 from the direct-current position to the alternate-current position, but will provide the necessary ribbon tension under all conditions.

In changing the type of motor, it is unnecessary to substitute the plates 116 and 118, since both plates are originally designed to permit quick and easy elimination or addition of gears.

In lieu of substituting a shorter bracket for the bracket shown, the bracket 144 may be angularly positioned as shown in dotted lines in Figure 2. This arrangement permits the use of a single bracket irrespective of the type of motor employed. I have also found that a double set of holes may be provided in the bar 109 and the ring 26 for the bolts 111, thereby permitting the motor to be shifted and aligned with the bracket 144. In other words, the motor will be shifted instead of the bracket.

A plurality of holes 148 is provided in the back 14, so that the cabinet may be effectively ventilated.

Without further elaboration the foregoing will so fully explain my invention that others may, by applying current knowledge, readily adapt the same for use under various conditions of service.

I claim:

1. The combination with a casing having a sight opening, of a traveling endless band positioned within the casing, a plurality of spools carrying said band and arranged for dividing the band into a plurality of reaches, one of said reaches extending across said sight opening, brackets for mounting said spools, one of said brackets being pivotally mounted, automatic tensioning means connected with said movable bracket, one of said spools constituting a driving spool, a motor, transmission means connecting the motor with said driving spool, the bracket supporting said last named spool being shiftable for accommodating transmission means of different speed ratios when substituting a direct-current motor for an alternating-current motor, or vice versa.

2. In an advertising device, a traveling endless band, spools for guiding said band, brackets for supporting said spools, a driving spool, a bracket for supporting the latter, a motor, gearing connecting the motor with said last named spool, said last named bracket being shiftable for accommodating gearing of different speed ratios.

3. The combination with a casing having

- a sight opening, of a traveling endless band positioned within the casing, a plurality of spools carrying said band and arranged for dividing the band into a plurality of reaches, 5 one of said reaches extending across said sight opening, brackets for mounting said spools, one of said brackets being pivotally mounted, automatic tensioning means connected with said movable bracket, one of said 10 spools constituting a driving spool, a motor, gearing connecting the motor with said driving spool, the bracket supporting said last named spool being shiftable for utilizing only a portion of said gearing when substituting a slower speed motor, or vice versa. 15
4. In an advertising device, a traveling endless band, spools for guiding said band, brackets for supporting said spools, a driving spool, a bracket for supporting the latter, a motor, gearing connecting the motor with said last named spool, said last named bracket being shiftable for utilizing only a portion of said gearing when substituting a slower speed motor, or vice versa. 20
- 25 5. The combination with a casing having a sight opening, of a traveling endless band positioned within the casing, a plurality of spools carrying said band and arranged for dividing the band into a plurality of reaches, one of said reaches extending across said sight opening, brackets for mounting said spools, one of said brackets being pivotally mounted, automatic tensioning means connected with said movable bracket, one of said 30 spools constituting a driving spool, a motor, gearing connecting the motor with the spool, the bracket supporting said last named spool being shiftable for utilizing only a portion of said gearing when substituting a slower speed motor, or vice versa, and illuminating means disposed within said casing. 35
- 40 6. In an advertising device, a traveling endless band, spools for guiding said band, brackets for supporting said spools, a driving spool, a bracket for supporting the latter, a motor, gearing connecting the motor with said last named spool, said last named bracket being shiftable for accommodating gearing of different speed ratios, so as to permit motors of different sizes and/or speeds to be connected with said last named spool without necessitating reconstruction of the device. 45
- 45 7. An advertising device comprising a casing having a sight opening, a supporting frame disposed within said casing, an endless band carrying indicia, a plurality of spools for guiding said band, brackets associated with said frame for supporting said spools, said spools being arranged for dividing said band into a plurality of reaches, one of said reaches extending across said sight opening, one of said brackets being pivotally mounted, means connected with said movable bracket 50
- tending to move the same in a direction placing the band under operating tension, one of said spools constituting a driving spool, a motor, speed reducing means connecting the motor with said driving spool, the bracket supporting said driving spool being shiftable to change the location of the driving spool so that only a portion of said speed reducing means may be utilized for accommodating a substitute motor having a slower speed, or vice versa. 55
- 80 8. An advertising device comprising a casing having a sight opening, a supporting frame disposed within said casing, an endless band, a plurality of spools for guiding said band, brackets associated with said frame for supporting said spools, said spools being arranged for dividing said band into a plurality of reaches, one of said reaches extending across said sight opening, one of said brackets being pivotally mounted, means connected with said movable bracket tending to move the same in a direction placing the band under operating tension, one of said spools constituting a driving spool, a motor, speed reducing means connecting the motor with said driving spool, the bracket supporting said driving spool being shiftable to change the location of the driving spool so that only a portion of said speed reducing means may be utilized for accommodating a substitute motor having a slower speed, or vice versa, and illuminating means positioned within said casing. 85
- 90 9. In an advertising device, a traveling endless tape, a plurality of means for supporting and guiding said tape, one of said means comprising a driving element for the tape, a motor, a mounting for the motor, said mounting being provided with first and second openings, bolts associated with the motor and passing through said first openings to fasten the motor to the mounting, and gearing connecting the motor with said driving element, said second openings being arranged to receive the bolts associated with a motor of slower speed and placed in a different position to permit only a portion of said gearing to be used. 95
- 100 10. In an advertising device comprising a cabinet, a traveling member provided with advertising indicia and positioned within said cabinet, and a frame for supporting the traveling member, said frame comprising two spaced end members and a plurality of bars connecting the same into a unitary structure, said frame occupying the bottom portion of said cabinet to permit the traveling member to be mounted in the remaining upper space, and illuminating means positioned within the contour of said frame for illuminating the space above the frame. 110
- 115 In testimony whereof I hereunto affix my signature.
- SIGMUND REST.
